INVENTOR

BY F. D. THOMASON.

ATTORNEY

UNITED STATES PATENT OFFICE.

JOHN H. SAMPSON, OF CHICAGO, ILLINOIS, ASSIGNOR TO CHARLES J. BARNES, OF SAME PLACE.

MAP OR CHART EXHIBITOR.

SPECIFICATION forming part of Letters Patent No. 364,675, dated June 14, 1887.

Application filed December 2, 1886. Serial No. 220,452. (No model.)

To all whom it may concern:

Be it known that I, JOHN H. SAMPSON, of Chicago, in the county of Cook and State of Illinois, have invented certain new and useful 5 Improvements in Charts and Hanging Fixtures and Cases therefor; and I do hereby declare that the following is a full, clear, and exact description of the invention, which will enable others skilled in the art to which it applies 10 pertains to make and use the same, reference being had to the accompanying drawings, and to letters of reference marked thereon, which form a part of this specification.

Heretofore charts having maps or illustrations on one side only have been made, which could only be suspended in map-cases or cabinets, and could not be removed therefrom and hung up on the wall or elsewhere.

It is the object of my invention to so make the chart, its hanging fixtures, and the case adapted to receive it, that said chart may be hung just as conveniently to the wall as in the map-case, and so that said chart may have a map, diagram, or illustration made on both sides which can be easily exposed, substantially as hereinafter more fully described, and as illustrated in the drawings, in which—

Figure 1 is a front perspective of my map-case, showing some charts removed. Fig. 2 is 30 a transverse vertical section taken on line xx , Fig. 1, looking toward the nearest end of the case. Fig. 3 is a transverse vertical section taken on line yy , Fig. 1, looking in the opposite direction. Fig. 4 shows a front elevation 35 of one end of my map-case, showing modified means for securing the map-fixtures therein. Fig. 5 is a detail view showing one of the strips or slats I use for mounting the map-hanging fixtures; and Fig. 6 shows a rear and 40 sectional view, respectively, of a portion of slat having modified form of hanging fixtures affixed thereto.

Reference being had to the drawings, A represents a rectangular case or cabinet provided 45 with a suitable cover and adapted to be hung on the wall.

B represents the slats or strips of board on which are mounted the fixtures for hanging the spring-rollers around which the charts C 50 are wound. It will be observed that by turning the slats with one longitudinal edge up-

permost, so that the chart unrolls from above, one side of the chart will be exposed, while by turning said slat so that its opposite longitudinal edge will be uppermost the chart will unwind from underneath and the opposite surface of the chart will be exposed, substantially as illustrated in the case in Fig. 2. In order that said slat B may be suspended from the wall, so that either side of the chart C may be exposed, I provide screw-eyes on both longitudinal edges of the slat, preferably the same distance apart, as shown in Fig. 5. A plate, e, with a hole in it may be sunk into and secured to the back of the slat B, though having the portion of the said slat back of and in register with the hole in said plate gouged away may answer just as well as the eyes hereinbefore referred to. In order that the slat may be placed and secured in the cabinet 70 or case A, I make in one end of said case, contiguous to the back thereof, rectangular recesses $b b b$, and in the other end I form a corresponding number of L -shaped recesses, $c c c$. The horizontal arm of recesses c extends to the front edges of the end of the case A, and the lower extremity of the perpendicular part of said recess c is in alignment with the lower extremity of recess b . In order to secure said slat in the case A, I place one end 80 thereof in the recess b , and then push the other end thereof into the perpendicular part of recess c . The slat is thus held securely in place, and yet can be easily removed and reversed for the purpose of exposing the opposite side 85 of the chart when desired.

I do not wish to be confined to the means hereinbefore described for securing the slats B in the case A, because any mechanic can readily devise means for so doing. For example, in Fig. 4, instead of recesses $c c$, I provide pins E, which project horizontally outward from the bottom of the case and enter corresponding holes in or near the ends of the slats B. Then, in order to prevent said slats 95 from falling outward, I have the bolts F pushed into their ends from the outside of the case, as shown. The pins E and bolts F may be used at one end in conjunction with the recesses b at the other end of the case; or the bolts F and pins E may be used at both ends of said case, as desirable.

The principal features of my invention are the reversibility of the slat, thus enabling one to expose either side of the chart, and the ease with which the chart can be removed from the case and transferred to the walls. Two maps of the same set can in this way be exposed at one and the same time, and the ease as compared to other cases of the same dimensions can contain twice as many maps or charts.

10. What I claim is—

1. The combination, with a sheet of suitable fabric having maps, diagrams, or illustrations on both sides, and roller upon which the same is wound, of a slat, B, in which said roller is journaled, and means for suspending said slat with either horizontal edge uppermost.
2. The combination, with a sheet of suitable fabric, roller upon which the same is wound, and removable slat B, in which said roller is journaled and removable therewith, of a case, A, and means for securing said slat therein.
3. The combination, with a sheet of suitable fabric having maps, illustrations, or diagrams on both sides thereof, roller upon which the

same is mounted, and removable slat B, in which said roller is journaled and is removable with, of a case, A, and means for securing said slat therein.

4. The combination, with a sheet of suitable fabric, roller upon which the same is mounted, and removable slat B, in which said roller is journaled and removable with, of case A, provided with rectangular recesses b at one end, adapted to receive one end of said slat, and means for securing the opposite end of said slat in position.

5. The combination, with a sheet of suitable fabric, roller upon which the same is wound, and removable slat B, in which said roller is journaled and removable with, of a case, A, having rectangular recesses b in one end, and T-shaped recesses c in the opposite end, as and for the purpose set forth.

JOHN H. SAMPSON.
